HARRY E. DOERR, OF ST. LOUIS, MISSOURI, ASSIGNOR TO SCULLIN STEEL COMPANY, OF ST. LOUIS, MISSOURI, A CORPORATION OF MISSOURI.

PEDESTAL TRUCK SIDE FRAME.

1,414,554.

Specification of Letters Patent. Patented May 2, 1922.

Application filed March 25, 1920. Serial No. 368,639.

To all whom it may concern:

Be it known that I, HARRY E. DOERR, a citizen of the United States, residing at St. Louis, in the county of St. Louis and State 5 of Missouri, have invented certain new and useful Improvements in Pedestal Truck Side Frames, of which the following is a specification.

This invention relates to pedestal truck 10 side frames.

In my copending application, Serial No. 347,976, filed December 29, 1919, I have disclosed a pedestal truck side frame, including pedestal jaws, which may be applied to 15 a Master Car Builders' journal box between the inner bolt lugs of the latter and the dust guard housing, whereupon the side frame and journal box may be moved relatively laterally to each other to their normal relative positions, in which position pedestal 20 jaw extensions act as an emergency fastening for maintaining the connection between the side frame and the journal box, and therefore for the wheels and axles, in the 25 event that the truck is derailed or is lifted from the track by any part other than the axles. Necessarily, the bearing surfaces, or the surfaces at the ends of the jaw extensions, which engage the sides of the journal 30 box in said application, are relatively narrow, being limited in width to an amount slightly less than the distance between the inner journal box bolt lugs and the dust guard.

The object of this present invention is 35 to provide an arrangement having the advantages of the invention set forth in my said copending application, and which at the same time provides greater bearing surfaces 40 between the pedestal jaw extensions and the journal box in a manner to meet all of the requirements for successful commercial operation.

This and other objects are accomplished 45 by means of the arrangement disclosed on the accompanying sheet of drawings, in which—

Figure 1 is a fragmentary side elevation 50 of a truck side frame embodying my invention, and shown as applied to a standard Master Car Builders' journal box;

Figure 2 is a top plan view of the same arrangement; and

Figure 3 is an end view of the side frame shown connected to a journal box of the 55 type above mentioned.

The truck side frame 10 here shown has pedestal jaws 11, the lower ends of which terminate in laterally extending portions 12, which extend toward each other lengthwise 60 of the side frame. These extending jaws 12 engage the sides of the Master Car Builders' journal box 13 intermediate its ends, and more particularly intermediate the vertical planes of the journal box bolt lugs 14. 65 As is apparent from the arrangement disclosed in the figures of the drawings, it will be impossible to apply the side frame to the journal box by a relative vertical movement while the jaw extensions 12 are intermediate 70 the journal box bolt lugs 14.

In my said copending application I applied the side frame to the journal box by lowering the jaw extensions downwardly between the inward journal box bolt lugs 14 and 75 the dust guard 15, but, as stated hereinabove, I found that there are certain advantages in having the jaw extensions of greater width and, as a matter of fact, of such a width that the jaw extensions cannot be accommodated 80 between the inner journal box lugs 14 and the dust guard 15. In this present case I have increased the width of the jaws 11, and particularly the lower ends thereof, including the extensions 12, to provide a relatively 85 greater bearing surface between the inner jaw extensions 12 and the sides of the journal box. Not only is the bearing surface increased, but the tendency for the journal box to twist within the jaws is reduced. The side 90 frame is provided with four housing lugs 16 which fit over the outside and embrace the four upper journal box bolt lugs 14. Accordingly, when the side frame is in operative position with respect to the journal box, 95 no accidental relatively lateral movement will occur between the parts in question. The side frame is applied to the journal box by moving the side frame laterally inwardly with respect to the journal box with the 100 side frame in a slightly elevated position so that the housing lugs 16 will clear the journal box bolt lugs 14, and when the side frame has been moved into a central position 105 with respect to the journal box, the side frame may be lowered into the operative

position shown in the figures of the drawing. In such position the pedestal jaw extensions act as an emergency fastening to prevent detachment of the parts when the truck is derailed or is lifted from the track by any part other than the axles.

What I claim as new is:

1. A pedestal truck side frame including pedestal jaws having portions which embrace bolt lugs of Master Car Builders' journal boxes normally to prevent relative lateral movement between the side frame and journal box, said pedestal jaws having portions which extend inwardly toward each other and embrace the sides of the journal box between the bolt lugs thereof for assisting in maintaining the operative position of said side frame and said journal box, said last mentioned jaw portions being of such dimensions as to provide relatively large bearing engagement with the sides of said journal box and whereby they must be applied to the side frame in a manner other
- 10
- 15
- 20

than between the inner journal box bolt lugs and the dust guard.

2. A pedestal truck side frame including pedestal jaws having four depending housing lugs which embrace lugs of Master Car Builders' journal boxes normally to prevent relative lateral movement between the side frame and journal box, said pedestal jaws having portions which extend inwardly toward each other and embrace the sides of the journal box between the bolt lugs thereof for assisting in maintaining the operative position of said side frame and said journal box, said last mentioned jaw portions being of such dimensions as to provide relatively large bearing engagement with the sides of said journal box and whereby they must be applied to the side frame in a manner other than between the inner journal box bolt lugs and the dust guard.

Signed at St. Louis, Missouri, this 20th day of March, 1920.

HARRY E. DOERR.
